UNITED STATES PATENT OFFICE.

ELWIN J. BABBITT, OF PETOSKEY, MICHIGAN, ASSIGNOR OF ONE-HALF
TO WILLIAM J. RICE, OF SAME PLACE.

HANDLE-BAR FOR BICYCLES, &c.

SPECIFICATION forming part of Letters Patent No. 650,963, dated June 5, 1900.

Application filed December 4, 1899. Serial No. 739,176. (No model.)

To all whom it may concern:

Be it known that I, ELWIN J. BABBITT, a citizen of the United States, residing at Petoskey, in the county of Emmet, State of Michigan, have invented a certain new and useful Improvement in Handle-Bars for Bicycles, &c., of which the following is a specification, reference being had to the accompanying drawings.

10 This invention relates to an improvement in adjustable handle-bars for bicycles and like vehicles, and has for its object a means of attachment of the handle-bar proper whereby the latter may be adjusted forwardly and 15 downwardly or rearwardly and upwardly by one movement of the said bar. It has heretofore been the practice to accomplish this object by two separate movements, and my invention is designed to obviate one of them.

20 With this main object in view my invention consists in the peculiar construction, arrangement, and combination of parts herein-after described, and then definitely claimed at the end hereof.

25 In the drawings accompanying this application, and which represent the preferred form of my invention, Figure 1 is a perspective view of a bicycle-head having my invention applied thereto. Fig. 2 is a vertical central section. Fig. 3 is a top plan, and Fig. 4 is a perspective view, of the fastening-clamp and a modified form of tightening the same. Fig. 5 is a detail with the locking device removed. Fig. 6 is a section through the line 35 *xx* on Fig. 2.

Referring now to the details of the drawings by letters, A represents the head of a bicycle of any desired construction, which is shown merely to illustrate the means of using 40 my improvement.

B represents a tube or stem, preferably adjustably secured in said head by the bolt and nut *b b'*. Projecting downwardly from this tube or stem B, and preferably integrally secured thereto at an acute angle, is the tube C, closed at its lower end by any desired means. This tube is flattened on its under side, so as to be substantially D-shaped in cross-section, and slidingly secured to this 45 50 D-shaped or flattened tube is the handle-bar clamp E, made, preferably, in the form of a

tube cut away on its under side, as shown at *e*, so as to allow the clamp to slide completely up to the top of the main stem B. This tubular clamp is likewise flattened to correspond with the flattened tube and to prevent its turning thereon. (See Fig. 6.)

Two arms F F project from the clamp and form a means of supporting the handle-bar G, which may be of any shape, but is preferably bent inwardly at *g* and secured to the tubular part of the clamp, as shown in Fig. 1. The lower part of the clamp E is split at *e'*, so as to allow of its being fastened on the tube C, and two perforated ears or lugs H H project from the clamp over the split portion *e'* and are provided with a bolt passing through the perforations, and on the outer end of this bolt is securely fixed a collar or nut *h*. Between this collar *h* and one of the ears H 70 works a lever I, which is threaded on the bolt and is designed, when moved in one direction, to screw against the ears, and thus secure the clamp on the tube, and when moved in the opposite direction to move away from the 75 ears, and thus release the clamp, so that it can be moved on the tube. If preferred, the collar or nut *h* may be loosely fastened on the bolt by riveting or upsetting the end of the latter and a coiled spring *h'* (see Fig. 5) secured over the bolt between the lever I and said collar or nut to prevent the latter from rattling.

It is obvious that instead of making the ears integral with the clamp a separate band J 85 may be provided, as shown in Fig. 4, and that in place of the lever I a wing nut or a nut with a serrated or milled edge may be used, the latter being shown at J in the same figure.

From the above description and the accompanying drawings it is seen that if the handle-bar is at the upper end of its movement the rider may adjust it both downwardly and forwardly by turning the lever I and, if he wishes, without leaving his saddle, and when 95 it is moved upwardly the handle-bars simultaneously move rearwardly, this forward or rearward movement being due to the angle at which the tube C is connected to the main tube or stem B.

100 It is evident that the tube C may be connected to the main stem B at a different an-

gle from that shown and that various other changes may be made from what I have illustrated as my preferred forms; but all of these changes will come within the spirit of my invention as covered by the following claim:

5 What I claim as new is—

In a steering device for cycles, the combination of a stem, a tube rigidly connected thereto and projecting downwardly at an angle therefrom, a clamp adjustably secured to said downwardly-projecting tube, arms projecting outwardly from said clamp, each arm comprising a permanent securing means for

a handle-bar, means for adjusting said clamp and its arms, and a handle-bar secured in 15 said projecting arms and movable with said arms and their clamp, substantially as described.

In testimony whereof I affix my signature, in the presence of two witnesses, this 2d day 20 of December, 1899.

ELWIN J. BABBITT.
